UNITED STATES PATENT OFFICE.

CHARLES E. HOPKINS, DECEASED, LATE OF PLAINFIELD, NEW JERSEY; BY THE PLAINFIELD TRUST COMPANY, ADMINISTRATOR, OF PLAINFIELD, NEW JERSEY.

CASTING MACHINE.

Original application filed March 2, 1922, Serial No. 540,481. Divided and this application filed November 17, 1924. Serial No. 750,242.

To all whom it may concern:

Be it known that CHARLES E. HOPKINS, deceased, who was a citizen of the United States, and a resident of Plainfield, in the county of Union and State of New Jersey, did invent certain new and useful Improvements in Casting Machines, of which the following is a specification.

This invention relates to a metal pump for metal casting machines and has for its main object and feature the provision of a pump, for feeding metal to a closed casting chamber, in which the usual spring relief generally employed in devices of this character will not be necessary and in which the metal will be maintained at a proper temperature.

This application is a division of application Ser. No. 540,481, filed March 2, 1922. In the accompanying drawings the invention is disclosed in a concrete and preferred form in which:

Fig. 1 is a side elevation of a metal pump embodying the invention.

Fig. 2 is a vertical sectional view.

11 and 12 indicate mold members forming a closed mold with which communicates the constantly open nozzle 99 carried by spout 10 leading to melting furnace A. This spout may conveniently be formed integral with cross frame E, and terminates in what is virtually a fixed hollow plunger 86. 87 is the pump chamber sliding up and down with respect to plunger 86, said chamber having a valve opening 94 in its bottom. Said pump chamber is actuated by a tie rod 89, extending below opening 94, and this tie rod is carried by two vertical rods 88, one on each side of the cylinder or pump chamber and extending loosely through guides 88^a thereof. At their upper ends rods 88 are connected by a short shaft 90, and connected to this shaft is a rod 91 the upper end of which is mounted on arm 92 of rock shaft 93 carried by the framework of the machine.

94^a is a spring coiled about shaft 93 and with one end anchored on the framework. The tension of this spring normally tends through the connections described to move the pump cylinder down. Other means, to be presently described, turn shaft 93 in the other direction to lift the pump chamber. It will be understood that, when the connec-

tions are raised, cross piece 89 will be moved upwardly until opening 94 is closed and that thereafter said cross piece will lift the pump cylinder, thereby feeding metal up through the spout. On the reverse movement, when spring 94^a is effective, collars 95, on rods 88, will engage the top of the cylinder and force it down, thereby overcoming the tendency of the plunger and cylinder to adhere and thereby, at the same time, opening valve 94. Continued movement of the parts in the same direction will then lower the pump cylinder completely and allow metal to flow in through opening 94.

96 indicates an equalizing chamber or auxiliary reservoir above nozzle 99. The capacity of the pump cylinder, the spout and the equalizing chamber is such that a full stroke of the cylinder will raise the molten metal to a level above nozzle 99 so that the equalizing chamber acts as a head for the casting chamber. This construction renders unnecessary the usual spring relief generally employed in connection with pumps that feed metal into a closed chamber, and also avoids the disadvantage of the usual open-mouthed casting chamber which is devoid of a feeding head at a higher level than the nozzle. This construction also permits the use of a heating element, such as the Bunsen burner 97, in the equalizing chamber, this burner being preferably so positioned that its frame is directed toward nozzle 99. The metal is thus prevented from congealing. Nozzle 99 is always open and the flow of metal therethrough is governed entirely by the pump. 98 indicates an air vent to permit the air to escape as the metal rises and also to admit air to sustain combustion in the gas burner.

Any suitable means may be employed to actuate rockshaft 93, but preferably an arm 100 and a rod 101 operated by a crank or cam are employed.

I claim:

1. A casting machine comprising: mold members, a reservoir of molten metal, connections, including a nozzle, for conducting metal from the reservoir to the mold members, an auxiliary reservoir in communication with said connections and nozzle and located above the latter, and a pump for feeding metal through said connections.

and nozzle and into the auxiliary reservoir to create a head of metal above the nozzle.

2. A casting machine comprising: mold members, a reservoir of molten metal, connections, including a nozzle, for conducting metal from the reservoir to the mold members, an auxiliary reservoir in communication with said connections and nozzle and located above the latter, and a pump for feeding metal through said connections and nozzle and into the auxiliary reservoir to

create a head of metal above the nozzle and a heating element in said auxiliary reservoir above the head of metal.

Signed at Plainfield, in the county of 15 Union and State of New Jersey, this 12th day of November, 1924.

THE PLAINFIELD TRUST COMPANY.
Administrator of Charles E. Hopkins, deceased.

By H. DOUGLAS DAVIS,
Asst. Secty. and Trust Officer.
